UNITED STATES PATENT OFFICE

EDWARD JOSEPH DONNELLEY, OF WESTERN SPRINGS, ILLINOIS, ASSIGNOR TO WESTERN ELECTRIC COMPANY, INCORPORATED, OF NEW YORK, N. Y., A CORPORATION OF NEW YORK

APPARATUS FOR FILING SHEETS OF MATERIAL

Application filed July 6, 1927. Serial No. 203,696.

This invention relates to an apparatus for filing sheets of material, such as tracings, and more particularly to a cabinet provided with drawers in which the sheets are filed under pressure.

In filing tracings or blueprints and the like, which are to be stored for a long period of time so as to preserve them for future reference and to which reference must be had from time to time, it is desirable that the sheets be filed in such a manner as to be protected from light and dust and yet be readily accessible. Many different devices have been proposed for filing sheet material, some of which are adapted for particular sizes of sheets such, for instance, as are conventionally used in correspondence. The present invention was devised in response to a demand for a filing apparatus for sheets of a somewhat larger size than stationery and embodying certain desirable features of protection and accessibility.

It is an object of the present invention to provide an apparatus which is especially adapted to filing sheets, such as tracings or blueprints and keep them in a protected but readily accessible condition.

In order to attain the above mentioned and other objects, the invention contemplates the provision of a filing apparatus having a drawer in which the sheets are filed under a weighted, flexible, dustproof covering. In accordance with one embodiment of the invention the covering is attached to the back of the drawer to prevent the sheets from creeping over the back of the drawer and becoming damaged.

It is believed that a complete understanding of the invention may be had by reference to the following description taken in conjunction with the accompanying drawing, in which

Fig. 1 is a perspective view of a filing cabinet showing a drawer extended;

Fig. 2 is a fragmentary plan view of a drawer, and

Fig. 3 is a sectional view taken on line 3—3 of Fig. 2.

Referring to the drawings in which similar reference numerals designate the same

parts in the several views, the numeral 6 designates a filing cabinet generally, which has a plurality of drawers 7 of a convenient size for filing tracings, blueprints or other sheet material. Each drawer is provided with a flexible, dustproof covering 8 of brown ducking or similar material which is attached to the back of the drawer so as to be flush with the top of the drawer. The covering 8 is of the same width as the drawer and extends from the back to the front of the drawer, where it is provided with a transverse weighting strip 9 of steel or other suitable material secured to the covering by folding the end of the covering over the strip and then sewing the end to the covering. A similar weighting strip 11 is secured intermediate the ends of the drawer by sewing a piece of ducking material over the strip, leaving the under surface of the covering smooth throughout its entire length. The best position of the weighting strip 11 has been found to be slightly forward from the center of the drawer since the tracings or blueprints exhibit a tendency to raise up and form a transverse bead or ridge at this point.

When a pile of tracings 12 is placed in a drawer and the covering 8 is put in place, the weighting strips 9 and 11 tend to compress the tracings so as to exclude the air from between the sheets, thereby eliminating the weathering effects found in tracings which have been exposed to the atmosphere for some time, and keeping the sheets smooth and of neat appearance. The brown ducking also keeps out all light and dust, and by reason of the fact that it is attached to the back of the drawer it prevents the sheets from extending over the back end of the drawer and permits the covering to be easily raised at the front of the drawer for the purpose of filing or removing sheets. By thus filing the tracings under pressure the capacity of the drawer is increased and the possibility of damaging the tracings in opening the drawer due to warped portions of the tracings extending above the height of the drawer is obviated.

It will be understood that the embodiment of the invention herein described and illus-

trated is merely a convenient and useful form of the invention, which is capable of many other modifications without departing from the spirit and scope of the invention.

What is claimed is:

5. 1. In a drawer for filing sheet material, a plurality of weights for retaining the sheets compactly in the drawer, and a flexible covering cooperating with the weights to exclude air and dust from the sheets, said covering being attached to the back of the drawer and extending to the front of the drawer.
10. 2. In a drawer for filing sheet material, a flexible covering extending over the sheets, a weight attached to the covering in a position to rest on the front ends of the filed sheets, and a second weight attached to the covering in a position to prevent the formation of ridges in the filed sheets.
15. 3. In a drawer for filing sheet material, a flexible dust proof covering attached to the back of the drawer at a point flush with the top of the drawer and extending to the front thereof, a weight attached to the front of the covering, and a weight attached to said covering at a point intermediate the ends thereof.
20. 4. In a drawer for filing sheet material, a flexible dust-proof covering attached to the back of the drawer at a point flush with the top thereof and extending to the front thereof, a weight attached to the front of the covering and extending transversely of the covering substantially to the edges thereof, and a second weight attached to the covering at a point intermediate the ends thereof and extending transversely of the covering to substantially the edges thereof.
25. 5. In a drawer for filing sheet material, a weight adapted to rest upon the ends of the sheets at the front of the drawer, and a flexible covering extending over the sheets and attached to the weight and immediately to the back of the drawer to prevent the sheets from creeping over the back of the drawer.
30. 6. In a drawer for filing sheet material, a flexible covering attached immediately to the rear of the drawer for preventing the sheets from creeping over the back of the drawer and for excluding dust from the sheets, and a weight associated with said covering for subjecting the sheets to compression.
35. 7. In a drawer for filing sheet material, a flexible covering attached immediately to the back of the drawer for preventing the sheets from creeping thereover, and a weight secured to the covering slightly forward of the middle of the drawer to prevent warping of the material at that point.

In witness whereof I hereunto subscribe my name this 18th day of June, A. D., 1927.

EDWARD JOSEPH DONNELLEY.
